UNITED STATES PATENT OFFICE.

JAMES H. CAHILL, AND RALPH H. KINGDON, OF CHICAGO, ILLINOIS, ASSIGNEES TO SEARS, ROEBUCK AND CO., OF CHICAGO, ILLINOIS, A CORPORATION OF NEW YORK.

PNEUMATIC PAINTBRUSH.

Application filed October 7, 1922. Serial No. 592,945.

To all whom it may concern:

Be it known that we, JAMES H. CAHILL and RALPH H. KINGDON, citizens of the United States, residing at Chicago, in the county of Cook and State of Illinois, have invented a certain new and useful Pneumatic Paintbrush, of which the following is a specification.

This invention relates to an improved pneumatic paint brush and aims to provide a novel brush which is so constructed that it may be quickly and easily dismembered and reassembled to permit of cleaning and oiling, or substitution of nozzles.

Another object of the invention lies in the provision in a pneumatic paint brush of a unitary demountable paint conduit which, together with its nozzle, may be readily attached or detached by operating a single locking member on the brush.

Another object is to provide an extremely simple paint nozzle and to mount it in such a way that it may be easily removed and replaced by other nozzles having different sized passages therethrough.

Another object resides in the provision of an improved paint valve cooperating with the paint nozzle with a wedging action to preclude the possibility of any leakage of paint from the brush when it is not in use.

Another object consists in the provision in the air conduit of a tubular air valve operating member which is adapted to serve as a conduit for the passage of air therethrough after unseating the valve.

A further object consists in the novel arrangement of the air valve and its operating member whereby a quick detachable operating connection is afforded between the air valve and the paint valve to enable the operation of both valves in the proper sequence by a single trigger.

A still further object consists in the novel construction and arrangement in the spray head of the brush hereinafter to be described wherein all of the passages may be made straight and hence can be cleaned more readily.

The invention further contemplates the provision of a brush of the character described which is of a balanced construction wherein the paint and air line hose connections are arranged so that they do not

hinder the operator in directing the paint stream upon the surface being coated.

Other minor objects and advantages will be pointed out as the following description progresses.

In the drawings illustrating a preferred embodiment of our invention, Figure 1 is a side view in elevation of the paint brush with its paint and air line hose connections. Fig. 2 is a longitudinal vertical section thereof. Figs. 3 and 4 are respectively front and rear end views. Fig. 5 is a transverse vertical section taken on the line 5—5 of Fig. 2. Fig. 6 is a view partly in elevation and partly in section showing the brush with its paint conduit in disassembled relation. Fig. 7 is a plan view of the main portion of the brush as it appears in Fig. 6, with the paint conduit removed. Fig. 8 is an underside plan view of the paint conduit, the paint valve and appurtenant parts of which have been removed. Fig. 9 is a view of the locking bolt and its coacting elements shown in perspective in dissociated relation, and Fig. 10 is a similar view of the parts forming the operating connection whereby the air valve and the paint valve are operated by the same trigger.

Throughout the views the same reference numerals are applied to the same parts.

Referring to the drawings, the device comprises generally a paint conduit 11 and an air conduit 12 mounted in operative relation in a handle 13 and having connections with the paint line 14 and air line 15 through the usual hose connection. The paint and air are both furnished under the requisite pressure in a manner well understood in this art. The operation of the brush is controlled in a manner hereinafter to be described, by the use of a trigger 16 which, the operator actuates with his forefinger while supporting the brush by the handle and directing the paint stream upon the object or surface being coated.

The handle 13 is preferably cast with an integral hollow boss 17 joining the parallel vertical side walls 18 and 19. Extending through the cylindrical opening 20 provided in the boss 17 is an air connection 21 which is internally threaded as at 22 to receive the externally threaded inner end of the air conduit 12. The latter comprises

a spray head portion 23 having a cylindrical shank 24 of reduced cross section. The shank 24 comprises a further reduced stem portion 25 eccentric with respect to the shank 24 as most clearly appears in Fig. 6, the inner end of which threads into the air connection 21 as shown in Fig. 2. A shoulder 26 is presented on the shank 24 at the reduced stem portion 25 which abuts the forward edge of the side walls 18 and 19 of the handle 13. In this way the air conduit 12 may be rigidly mounted in the handle 13 by threading the air connection 21 upon the stem 25 by means of a wrench engaged with the facet 27 provided on the air connection. The stem portion 25 of the air conduit 12 is milled to provide vertical channels 28 on opposite sides as most clearly appears in Fig. 7 to permit the movement 20 of the trigger 16, the two legs 29 of which straddle the stem 25 and are pivotally mounted on the walls 18 and 19 on pins 30 permanently engaged therein.

Coacting with the legs 29 of the trigger 16 is a sliding follower 31 which is in the form of a plate having lateral lugs 32 for engaging the inner edges of the legs of the trigger (see Fig. 10) and a narrow depending vertical lug 33 movable longitudinally 30 of the stem 25 in a slot 34 provided in the wall thereof and opening into the longitudinal bore 35 provided therein. The follower 31 fits over a block 36 which is secured by means of a screw 37 to a tube 38 fitting snugly within and slidably longitudinally in the bore 35. When the trigger 16 is pulled, the oscillation thereof communicates reciprocatory movement to the follower 31 which is transmitted through the block 36 to the tube 38. The latter upon sliding inwardly is adapted to unseat a ball valve 39 urged to seat in the inner extremity of the bore 35 by means of a coiled tension spring 40 operating in the bore 41 of the air line connection 21. The tube 38 has a longitudinal secondary bore 42 adapted to permit the passage of air therethrough when the valve 39 is unseated. The inner extremity of the tube 38 is notched as shown at 43 suitably to reduce the end thereof to provide a bypass for the air under pressure past the valve 39 when the latter is held off its seat.

Communicating with the bore 35 of the air conduit 12 is a central air discharge orifice 44 and a lateral air discharge duct 45 which extend into the spray head portion 23 of the air conduit 12. The central orifice 44 is adapted to jet a stream past the mouth of a paint discharge nozzle 46 extending diagonally through an opening 47 in the spray head 23 in front of the orifice 44. The nozzle 46 has a paint discharge orifice 48 the size of which is variable to suit 60 the particular grade or kind of paint or

other substance with which the brush is being operated. The duct 45 terminates on the front face of the spray head 23 where an annular chamber 49 is provided between the head 23 and an annular plate 50 secured upon the spray head by a gland nut 51. The plate 50 has an annular inturned flange 52 engaging the conical recess 53 in the head 23, the relative size of the flange 52 being such that the plate 50, when secured upon the spray head 23 by a tool engaging in the slots 54, leaves a substantial space between the plate and the head to provide the annular chamber 49. The plate 50 is bored to provide jet openings 55 at 70 diametrically opposite sides above and below the central orifice 44 and converging to a point in front of the spray head 23 to flatten or flare out the paint stream so that a section thereof would appear as a straight 80 line in a manner and for a purpose well understood in this art. It will be seen that by virtue of this arrangement the passages in the head and the removable plate may be made straight and hence may be easily bored 90 and also may be cleaned more readily upon the removal of the plate.

The shank portion 24 of the air conduit 12 is milled out on its upper surface to provide a longitudinal channel 56 extending forward to a point in back of the spray head 23 as most clearly appears in Figs. 2, 6 and 7. At this point the bottom of the channel inclines upwardly to provide a seat 57 for the paint nozzle 46. It is through this portion that the opening 47 is provided to receive the nozzle 46. The paint conduit 11 as indicated in Fig. 6, is demountable from or attachable to the brush by movement in a line extending at an acute angle 100 to the axis of the air conduit 12 to enter the paint nozzle 46 through the opening 47, it being understood that the paint nozzle has a loose fit in the opening 47 and a comparatively snug or tight fit in the cylindrical 110 recess 58 provided in the paint conduit 11 so that the nozzle is removable with the paint conduit as a unit.

The paint conduit 11 is generally rectangular in cross section and is arranged to fit closely between the walls 18 and 19 of the handle 13 when its forward end is entered into the channel 56 of the air conduit with the nozzle 46 entered in the opening 47 as described. The paint conduit 11 is milled out on its opposite sides as most clearly appears in Figs. 6 and 8 to provide channels 59 wherein the upper extremities of the legs 29 of the trigger 16 are adapted to oscillate 120 in operation. The paint conduit 11 is of reduced cross section at the point which overlies the slot 34 in the stem 25 of the air conduit 12 as shown at 60 in Fig. 2. The shank portion 61 thus formed is externally 125 screw threaded at its inner extremity to 130

make connection with the air line hose 14 in any suitable manner. Operating in a longitudinal bore 62 in the forward or head end of the paint conduit 11 is a paint valve 63 in the form of a cylindrical stem having a rounded head 64 adapted to coact with the inner end of the paint nozzle 46 projecting into the recess 58 in the conduit 11 diagonally with respect to the valve. The valve 63 in its reciprocation is arranged to close a duct 65 leading to the nozzle 46 from the passage 66 in the paint conduit 11. The valve 63 in this way serves as a throttle valve to close the duct 65 and it also seats 10 with a wedging action upon the inner end of the nozzle 46 to close the discharge orifice 48 thereof. The paint valve 63 similarly to the tube 38, which operates to open the air valve 39, is provided with annular 15 grooves in which solid grease or graphite is packed when the device is assembled so that the action of the members in the bores will be rendered easy and there will be no possibility of leakage past the same.

20 The inner end of the valve 63 protrudes from the conduit 11 over the slot 34 provided in the stem portion 25 of the air conduit 12 and is there provided with an enlarged annular shoulder in the form of a rigid collar 67. Engaging the rear face of the collar 67 is a coiled tension spring 68 mounted on a cylindrical extension 69 of a block 70 secured upon the shank portion 61 of the conduit 11 by means of a screw 71.

25 The valve 63 by virtue of this arrangement is held yieldingly to seat against the paint nozzle 46 closing the duct 65 as appears in Fig. 2. The valve 63 is arranged to be opened in the reciprocation of the follower 30 31 by the engagement of a lug 72 which projects upwardly in front of the collar 67 and partly encircles the protruding stem of the valve 63 (see Fig. 10). It will be noted from Fig. 2 that a lost motion operating 35 connection is provided between the air valve operating means and the paint valve. This is afforded by the displacement of the collar 67 longitudinally of the stem of the valve 63 away from the lug 72 of the follower 31. In this way the air valve 39 may be operated separately as when using the brush as a blower but will otherwise be unseated slightly before the valve 63 is operated so that there will be a flow of air under pressure 40 past the paint nozzle 46 before the paint is permitted to flow, and in a like manner the flow of air will continue when the paint valve is closed, the additional air which is permitted to flow being sufficient to draw out any paint remaining in the nozzle 46 so that we avoid clogging of the latter, which would result were any paint remaining therein permitted to dry.

45 The rear face of the block 70 opposite the stem portion 69 is cut on an incline as shown 50 at 73. Extending transversely across the face 73 is provided a semi-cylindrical groove 74 in which is adapted to engage a segmental portion 75 of a locking bolt 76 (see Fig. 9) which extends transversely between the walls 18 and 19 of the handle 13 as most clearly appears in Fig. 7. The bolt 76 as shown in Fig. 9 is cylindrical in form but is milled off to half its diameter as shown at 77, thus providing the segmental portion 75 intermediate the ends of the shank of the bolt. One end of the bolt 76 is enlarged, providing a head 78 engaging the outside of the wall 19 of the handle, while the opposite end is reduced to square form as shown at 79 to be received in an opening 80 of similar form provided in the operating finger piece 81. The latter is held on the bolt 76 by means of a screw 82 threading into the bolt 76. The face 73 being cut in a plane parallel with the axis of the paint nozzle 46 permits the removal of the paint conduit along a line extending at an acute angle to the brush as indicated in Fig. 6 when the locking bolt 76 is rotated through approximately 180° from the position shown in Fig. 2 so that the segmental portion 75 occupies the position illustrated in Fig. 6. It will thus appear that the paint conduit may with its nozzle be dismounted from the brush simply by operating a single locking element by the fingers. In order to avoid a projection from the side of the brush we prefer to form a recess 83 (Fig. 1) in the outside of the handle wall 18 wherein the finger piece 81 may swing.

55 It will thus appear that we have provided a pneumatic paint brush wherein the paint conduit, together with its nozzle, is readily demountable as a unit without the use of any tools. Furthermore, the remainder of the brush may be easily dismembered to permit of cleaning and oiling the parts. A further advantage of the construction which we have disclosed resides in the fact that the brush is well balanced since the weight of the conduits and the operating mechanism appurtenant thereto is offset by the weight of the paint and air line hose connections so that the operator in handling the brush is not hindered in directing the paint stream upon the surface being coated as has been the case with some brushes of this kind heretofore produced.

60 We realize that the embodiment herein disclosed is capable of considerable modification without departing from the spirit of our invention. It is therefore our endeavor in the appended claims to recite the invention in terms to comprehend all legitimate modifications and adaptations of the invention which would occur to one skilled in the art to which this invention relates.

65 We claim as our invention:

1. A pneumatic spraying device comprising

ing a handle, a pair of conduits supported by said handle, one of said conduits serving to conduct a liquid substance to be sprayed and the other the air adapted to serve as the medium whereby the liquid is transmitted in the form of a spray onto a surface to be coated, said air conduit being adapted to be removably supported by said handle, and said liquid conduit being demountably engageable with said air conduit, said conduits having interengaging portions, and a member on said handle adapted to be operated to hold said liquid conduit securely in operative relation to said air conduit or to permit the same to be dismounted.

2. A pneumatic spraying device comprising a handle, a pair of conduits adapted to be supported thereby in operative relation, one of said conduits serving to conduct a liquid substance to be sprayed and the other the air for transmitting the liquid in the form of a spray onto a surface to be coated, said air conduit being detachably supported by said handle, but adapted normally to be permanently secured thereto, said handle comprising extending walls, said liquid conduit being adapted to be demountably associated in operative relation with said air conduit in engagement between said walls and a locking member carried by said handle adapted to be operated to secure said conduits in assembled operative relation.

3. In a pneumatic spraying device the combination of a handle, a pair of conduits adapted to be supported thereby in operative relation, one of said conduits being adapted to conduct a liquid substance to be sprayed and the other the air to serve as the transmitting medium therefor, said handle comprising a projecting wall, one of said conduits being removably supported thereby, said conduits having portions adapted to be placed in register when said conduits are assembled in operative relation supported by said wall, and a quickly releasable locking member carried by said wall adapted to hold the other of said conduits in demountable relation to the first mentioned conduit.

4. In a pneumatic spraying device the combination of a handle, a pair of conduits adapted to be supported thereby in operative relation, one of said conduits being adapted to conduct a liquid substance to be sprayed and the other the air to serve as the transmitting medium therefor, one of said conduits being adapted to be removably supported by said handle and the other to be quickly demountable from operative relation with the first conduit, one of said conduits having a recess and the other a portion to engage in said recess in operative relation with said conduit, said demountable

conduit being removable by movement in a certain plane, and quickly releasable means to prevent such movement.

5. In a pneumatic spraying device the combination of a handle having spaced projecting walls, a pair of conduits adapted to be supported in operative relation thereby, one of said conduits conducting a liquid substance to be sprayed and the other the air to serve as the transmitting fluid therefor, one of said conduits being adapted to be permanently associated with but removably mounted in said handle and the other quickly demountable from operative relation with the first conduit, one of said conduits having a nozzle projecting therefrom and the other being provided with an opening to receive the same when said conduits are in operative relation, said nozzle and opening interfitting at one end of said device, said conduits being received between the walls of said handle at the other end, said demountable conduit being removable by movement along the axis of said nozzle and quickly releasable means operating between said spaced walls of said handle normally to prevent such movement.

6. In a pneumatic paint brush the combination of a handle, an air conduit adapted to be rigidly engaged with said handle, a paint conduit adapted to be demountably engaged with said air conduit and said handle, valves for said conduits, operating elements for said valves, and a single trigger for actuating said elements, said operating element for said paint valve having a lost motion detachable operating connection with said trigger.

7. In a pneumatic spraying device the combination of a handle having spaced projecting walls thereon, a pair of conduits adapted to be supported thereby in operative relation, one of said conduits conducting liquid substance to be sprayed and the other the air to serve as the transmitting medium therefor, each of said conduits having a control valve, a trigger having a forked portion permanently mounted in said handle between said spaced walls thereof, said conduits being mounted in operative relation in said handle projecting between the legs of said forked trigger, operating stems for said control valves and means engageable by the legs of said trigger for operating said stems.

8. The combination of a pair of fluid conduits operating jointly to discharge a combined stream of fluid, one of said conduits having a fluid passage therein, a nozzle, a valve operating in said conduit to control the flow of fluid through said nozzle, the other of said conduits having a bore therein, a discharge orifice at one end thereof, and a fluid connection at the other end, a valve seating to close said bore

against the flow of fluid to said conduit, a tube movable in said bore to unseat said valve, said tube having a passage for permitting the flow of fluid through said conduit, the wall of said conduit being slotted longitudinally of said bore, a member operating in said slot having operative connection with said tube to move the same, and means providing an operating connection 10 between said member and said valve for said first mentioned conduit.

9. In a pneumatic paint brush the combination of an air conduit having an air discharge orifice, an air line connection for 15 said conduit, a valve for controlling the flow of air to said conduit, a trigger for operating said valve, a paint conduit adapted to be operatively associated with said air conduit having a paint discharge nozzle extending therefrom, said air conduit being provided with an opening to receive said nozzle, said nozzle being adapted to be entered in or withdrawn from said opening by movement in a line at an angle to the 20 axis of said paint conduit, and means for holding said paint conduit in operative relation to said air conduit comprising a single movable member adapted in one position to permit movement along said line and in 25 another position to prevent such movement.

30 10. In a pneumatic paint brush the combination of an air conduit having connection with an air line, a paint conduit having connection with a paint line, said paint 35 conduit comprising a discharge nozzle adapted to project into said air conduit and removable as a unit with said paint conduit from said air conduit, said air conduit being provided with an opening to receive said nozzle, a locking member 40 permanently associated with said air conduit for holding said conduits in operative relation, said paint conduit being provided with means coacting with said locking member to prevent movement of said nozzle out of said opening to disassemble 45 said paint conduit from said air conduit.

50 11. In a pneumatic paint brush the combination of an air conduit having connection with an air line, a paint conduit adapted to be associated with said air conduit having connection with a paint line, said paint conduit comprising a nozzle, said air conduit being provided with an opening to receive said nozzle, said nozzle being adapted to be removably entered in said opening in a line inclined relative to the axis of 55 said air conduit, a locking member permanently associated with said air conduit, said paint conduit being provided with a transverse groove in a portion rigid therewith, said locking member being adapted in one position to lie in said groove to prevent relative movement of said paint con-

duit relative to said air conduit along said line and in another position to lie out of said groove to permit such movement.

12. In a pneumatic paint brush the combination of an air conduit having connection with an air line, a paint conduit adapted to be associated with said air conduit having connection with a paint line, said paint conduit comprising a nozzle, said air conduit being provided with an opening to receive said nozzle, said nozzle being adapted to be removably entered in said opening in a line inclined relative to the axis of said air conduit, a locking member permanently associated with said air conduit, a portion rigid with said paint conduit being formed with a surface disposed in a plane extending parallel with the line of movement of said nozzle, said surface being provided with a transverse groove, a segmental bolt carried by a part stationary with respect to said air conduit adapted in a holding position to project into said groove and in a releasing position to lie out of said groove flush with said surface to permit movement of said paint conduit in the plane of said portion toward or away from said air conduit.

13. In a pneumatic paint brush the combination of a handle having vertically projecting lateral walls, an air conduit permanently and removably mounted between said walls, said conduit being provided with an air valve, a trigger pivotally mounted between said walls straddling said air conduit adapted to operate said valve, a paint conduit adapted to be mounted in juxtaposition to said air conduit to operate in connection therewith, said paint conduit having a valve operated together with said air valve by said trigger, a paint nozzle projecting from said paint conduit in a line inclined to the axis of the air conduit, said air conduit being provided with an opening adjacent the discharge end thereof to receive said nozzle, and means acting between said handle and said paint conduit to prevent movement of said paint conduit in a line coincident with the axis of said nozzle to hold said paint conduit in operative relation to said air conduit.

14. In a pneumatic spraying device the combination of a fluid conduit having connection in a fluid line, a valve operating in said conduit to control the flow of fluid therethrough, spring means normally holding said valve in closed position, an abutment on said conduit for said spring means, a second fluid conduit having connection in a fluid line, a valve operating therein to control the flow of fluid therethrough, said conduits being adapted in operation to have detachable connection, means acting between said conduits engaging said

abutment to hold said conduits in operative relation, and a trigger for said conduits to operate said valves.

15. The combination in a device of the character described of a fluid conduit having a fluid passageway therein, said conduit being formed with an enlarged hollow conical spray head at the discharge end thereof, a central discharge orifice in said head, and a discharge duct extending from said passageway to the outer edge of the face of said head, an annular plate having an inturned flange protruding into said head to provide a fluid tight joint with the inside conical surface of said head, said plate and head in operative relation being adapted to provide an annular space therebetween, an annular member on said head to seal said space and hold said plate in operative position, said plate being provided with discharge orifices converging toward a point in front of said head to flatten the spray produced in the action of said central discharge orifice.

25. 16. In a device of the character described, the combination of a pair of fluid conduits adapted to cooperate to discharge a combined stream of fluid, a handle for supporting said conduits and directing the fluid stream discharged therefrom, fluid line connections for said conduits extending rearwardly therefrom past said handle, control valves for said conduits, operating means therefor, and a trigger operating on one side of said handle to actuate said operating means, said handle being made to extend downwardly from said device at said fluid line connections whereby the weight of said conduits and appurtenant operating connections is balanced on said handle with said fluid line connections.

40. 17. A pneumatic spraying device comprising, in combination, a handle, an air conduit detachably supported by said handle, a liquid conveying conduit supported by said handle and said first mentioned conduit, said liquid conveying conduit being quickly demountable from the other, and means for controlling the flow of fluid through said conduits.

45. 18. A pneumatic spraying device comprising, in combination, a handle having a pair of spaced upwardly projecting walls, an air conduit detachably supported by said handle between said walls, a liquid conveying conduit demountably supported above said air conduit between said walls, and means for controlling the flow of fluid through said conduit.

50. 19. A pneumatic spraying device having, in combination, a handle having spaced upwardly projecting walls, a conduit supported by said handle, a second conduit supported by said handle between said walls, said second conduit being quickly demount-

able, and operating means having forked legs straddling said conduits, said legs being pivotally connected to said walls at the upper ends.

55. 20. A pneumatic paint brush having, in combination, a handle, an air conduit detachably supported by said handle, a paint conduit demountably supported by said air conduit, valve means for said conduits, operating elements for said valve means, and a trigger for actuating said elements, the operating element for the paint valve having a lost motion connection with said trigger.

60. 21. A pneumatic paint brush having, in combination, a supporting means, an air conduit mounted on said supporting means, a paint conduit demountably supported in operative relation to said air conduit, said paint conduit being removable by relative movement in a substantially longitudinal plane, means for preventing such movement, and means for controlling the passages through said conduits.

65. 22. A pneumatic spraying device comprising, in combination, a handle, an elongated conduit having a connection in a fluid line, said conduit being provided with a longitudinal bore, a valve seating to close said bore against the flow of fluid, a tube movable in said bore to unseat said valve, said tube being provided with a longitudinal fluid passage, and means for moving said tube to unseat said valve.

70. 23. A pneumatic spraying device having, in combination, a handle, a conduit supported by said handle, a spray head on said conduit, a longitudinal channel in the outer surface of said conduit, an aperture extending from said channel into said spray head, a conduit positioned in said channel, a nozzle secured to said last mentioned conduit and extending through said aperture into said spray head, and means for controlling the passages through said conduits.

75. 24. A pneumatic paint brush having, in combination, a support, an air conduit mounted in said support, a spray head carried by said air conduit, a paint conduit mounted in operative relation with said air conduit, a removable paint nozzle supported in one end of said paint conduit and extending into said spray head, means for holding the paint conduit in position, and means for controlling the flow of fluid through said conduits.

80. 25. A pneumatic spraying device having, in combination, two fluid conduits, a nozzle having an orifice for discharging fluid from one of said conduits, means for forcing fluid through said conduit, a valve member for controlling the flow of fluid through said orifice, said valve member being movable toward said nozzle in a line at an angle to the axis thereof whereby to exert a wedging action on the face of said nozzle to effect a

sealing contact with said orifice, and means for operating said valve member.

26. A pneumatic spraying device having, in combination, a pair of conduits, a common support therefor, a nozzle for one of said conduits, said conduit being provided with a duct communicating with said nozzle, a valve member longitudinally movable at an angle to the axis of said nozzle, said valve

member in operation serving to close said duct and to move into engagement with said nozzle, and means for actuating said valve member and for controlling the flow of fluid through the other conduit.

In testimony whereof we have hereunto affixed our signatures.

JAMES H. CAHILL.

RALPH H. KINGDON.
